[57] ABSTRACT

A device for boats and trailers consisting primarily of a mounting channel and mounting bar secured to a base member carrying a pipe with a pivotable end having a tail and stop light secured to it, the pipe also having a protective rubber wheel and a locking handle for the upper pipe member.

5 Claims, 3 Drawing Figures

PATENTED JAN 29 1974

3,788,502

FIG. 1

FIG. 2

FIG. 3

BOAT GUIDE DEVICE

This invention relates to accessories for boat trailers and more particularly to a boat guide.

It is therefore the principal object of this invention to provide a boat guide which will be used in pairs and will be attached, one to each side of the trailer, the device is being swung away from the boat when launching or loading by overhead hoist or crane.

Another object of this invention is to provide a boat guide which will have tail and stop lights which will be pivoted away from the boat when using the launching ramp and the guides will serve to enable the launching and loading of the boat, easier.

Another object of this invention is to provide a boat guide of the type described which will hold the tail and stop light out of the water so as to prevent corroding and cause the bulbs to last longer.

Still another object of this invention is to provide a boat guide of the type described which will have a mounting channel and a mounting bar for attachment to the trailer by suitable fasteners and the pipe portion extending upwards, will include a bracket mounted rubber wheel for protecting the side of the boat hull from injury.

A further object of this invention is to provide a guide device of the type described which will have the upper pipe portion pivotable and the upper extremity of the main pipe member will include a locking handle for preventing the rotation of the upper pipe member.

Other objects of this invention are to provide a boat guide which is simple in design, inexpensive to manufacture, rugged in construction, easy to use and efficient in operation.

These and other objects will become readily evident upon a study of the following specification together with the accompanying drawing wherein:

FIG. 1 is a side view of the present invention shown in elevation and partly broken away;

FIG. 2 is a view taken along the line 2—2 of FIG. 1; and

FIG. 3 is a view taken along the line 3—3 of FIG. 1.

According to this invention, a boat guide 10 is shown to include a channel member 11 to which is secured an angle bracket 12 by means of a pair of bolt fasteners 13. A plurality of spaced apart openings 14 through channel 11 provide a means for receiving bolt fasteners in any desired position so as to adapt the channel 11 to trailers of various sizes. A quadrant 15 is welded to one end of channel 11 at the lower edges of its spaced apart plates 16. A plate 17 is welded between the side plates 16 and a plate 18 is welded also to the opposite edges of the side plates 16. A mounting bar 19 of L-shaped configuration is provided with a plurality of spaced apart openings 19' for receiving suitable bolt fasteners for mounting boat guide 10 to a trailer. The mounting bar 19 is secured to plate 18 of quadrant 15 by means of a pair of bolt fasteners 20 (one of which is shown). A pipe member 21 is externally threaded at one end and is pivotably carried within quadrant 15 by means of a bolt fastener 22 and a nut fastener 23. A loop member 24 is fixedly secured by welding or other means to the outer periphery of pipe 21, the loop 24 receiving a bolt fastener 25 carrying a nut fastener 26.

It shall be noted that the angular position of pipe 21 within quadrant 15, is adjustable by means of placing

the bolt fastener 25 in any one of the oppositely opposed openings 26 through the side plates 16.

A wheel bracket 28 is welded to the outer periphery of pipe 21 near its upper extremity, and serves to mount a rubber wheel 29 which is secured to bracket 28 by means of a bolt fastener 30 carrying nut fastener 31. Wheel 29 serves to prevent injury to the sides of the boat hull. An elbow member 32 is threaded onto the externally threaded end of pipe 21 and is welded at its opposite end to the horizontal pipe 33. At the opposite end of pipe 33 a U-shaped bracket 34 is secured to pipe 33 by means of bolt fastener 35 which receives fastener 36 threadably. An extension 37 of bracket 34 provides a means for mounting the license plate 38 which extends below the tail and stop light 39 which is secured fixedly in a suitable manner (not shown) to bracket 34. The wires 40 of tail and stop light 39 extend through pipe 33, pipe 21, and beneath the mounting channel 11.

A locking handle 41 is held to pipe 21 by means of an extending bolt 42, the elongated portion having spring means 43 for urging the opposite end against the serrated flange 44 of elbow 32. The locking handle 41 when pressed downwards against the pressure of spring 43 enables the flange 44 to be free so that the user may rotate the horizontal pipe 33 away from the boat so as to facilitate easy launching or loading thereof.

In use, guide 10 is used in pairs one each being secured by means of the mounting bars 19 and the channels 11 to the sides of the trailer carrying the boat.

What I claim is:

1. A boat guide for boat trailers, a quadrant member carried by said boat guide for pivotably carrying a pipe member having angular adjustment means including a loop, a bolt and nut fastener, a pair of side walls carried by said quadrant with a front and rear plate securing the side walls together, an L-shaped mounting bar member carried by said quadrant and a mounting channel member carried by said quadrant enabling said device to be secured as a pair, one to each side of a boat trailer, bracket and rubber wheel means carried by said pipe member for protecting the side of the boat hull from injury, a horizontal pipe member and elbow carried by said pipe with locking handle means for securing it in any desired position, a U-shaped bracket and tail and stop light carried by said horizontal pipe with bolt and nut fastener means for securing it thereto, an extension carried by said bracket for the mounting of a license plate.

2. The combination according to claim 1, wherein said side walls of said quadrant of said device are welded to one end of said mounting channel member and said pipe member within said quadrant is freely and pivotably carried within said quadrant and secured at its lower extremity by means of a bolt and nut fastener, said bolt fastener extending through said side plate and transversely through said pipe member enabling said pipe member to be adjustable angularly within said quadrant.

3. The combination according to claim 2, wherein a loop member secured fixedly to the outer periphery of said pipe on the interior of said quadrant, receives a bolt fastener which extends through any one of a plurality of oppositely opposed holes through said side plates, thus enabling the user to adjust the angle of said pipe with respect to the interior of said quadrant.

4. The combination according to claim 3, wherein an angle bracket is secured by suitable fasteners to said channel members and is adjustable by removing said bolts and placing them into any one of the plurality of openings through said channel member, and said mounting bar includes openings for receiving suitable bolt fasteners so as to mount said device through the combination of both said mounting bar and said mounting channel and a bracket is secured near the upper extremity of said pipe member carried within said quadrant, said bracket carrying said rubber wheel, said rubber wheel being held in position rotatably, by means of a bolt fastener through the center of said wheel, said bolt fastener receiving a nut fastener so as to render said wheel secured to said bracket carried upon said pipe and said elbow member threadably received at the upper extremity of said pipe within said quadrant includes a surrated flange, said surrated flange being in engagement with one end of said locking handle, said

locking handle being secured by bolt fastener means extending from said pipe and one end which forms a lever of said locking handle is secured to one end of a spring, the other end of said spring being secured to the outer periphery of said pipe, thus enabling the user to releasably disengage the opposite end of said locking handle from the surrations of said flange of said elbow in order that the horizontal pipe attached to said elbow may be pivoted away from said boat upon said trailer.

10

5. The combination according to claim 4, wherein the opposite end of said horizontal pipe secured to said elbow, carries said U-shaped bracket which is secured thereto, by means of a transverse bolt fastener including a threaded fastener thereon, said bracket being secured also to a tail and stop light and said bracket includes an extension to which said license plate is secured in a well known manner.
